UNITED STATES PATENT OFFICE.

ALEXANDER F. WARD, OF CHATHAM, ONTARIO, CANADA.

HOOP-COILING MACHINE.

SPECIFICATION forming part of Letters Patent No. 245,104, dated August 2, 1881.

Application filed April 27, 1881. (No model.)

To all whom it may concern:

Be it known that I, ALEXANDER F. WARD, of Chatham, in the county of Kent, Province of Ontario, Dominion of Canada, have invented 5 an Improvement in Hoop-Coiling Machines, of which the following is a specification.

The nature of this invention relates to certain new and useful improvements in a machine upon which hoops are coiled for shipment, and for which Letters Patent No. 223,968 10 were granted to me January 27, 1880; and the invention consists in the novel construction of the various parts and their several combinations, as more fully hereinafter set forth.

15 Figure 1 is a front elevation, showing the machine in use in coiling hoops. Fig. 2 is a side elevation with the front standard and drum in vertical central section. Fig. 3 is a partial perspective of the main shaft and its 20 immediate attachments. Fig. 4 is a vertical section on line 4 4 in Fig. 2. Fig. 5 is an enlarged perspective of a section of the band. Fig. 6 is a section on line 6 6, Fig. 1.

In the accompanying drawings, which form 25 a part of this specification, A represents a frame which carries the working parts of the device, and in this frame is journaled a shaft, B, upon which is secured the driving-wheel C, to which motion is communicated through the 30 pulley D from any suitable source of power. The pulley D is secured at the outer end of a counter-shaft, E, running in boxes a secured to the oscillating box F, the front end of which is pivotally secured to the frame A. A spring, 35 b, one end of which is secured to the frame by the stud-bolt e, passes rearward under the oscillating frame and holds it and the friction-wheel H, which is also secured to the counter-shaft E from contact with the face of the driving-wheel C, except when pressure is exerted 40 upon the treadle I, when by means of the connecting-rod J the friction-wheel H is forced into contact with the driving-wheel C, and communicates motion thereto and the shaft upon 45 which it is secured. This arrangement allows the pulley D to run constantly, while the working parts of the machine may be run intermittently without the necessity of loose pulleys.

50 Upon the front end of the shaft B is secured the coiling-disk K, the rear side of which is

provided with an annular flange, d, which is cut away at e. Upon the rear face of the disk is secured the dog L by means of the screw f. A slot, M, is cut through the disk coincident 55 with the cut-away portion of the flange thereon, and the dog L is compelled by the spring g to close against the inner face of the flange, as shown in Figs. 1 and 3, except when forcibly disengaged, as hereinafter described. The 60 dog is provided with an L-shaped arm, h.

Upon the shaft B there is sleeved a spider, N, provided with arms i, to the outer ends of which is secured the ring O, of a larger diameter than that of the coiling-disk K. The hub 65 l of this spider is cone-shaped at its forward end, so that when the spider is projected forward for the purpose of compelling the annular ring O to push the coil of hoops from the periphery of the coiling-disk the conical portion of the hub will actuate the arm h of the dog, and compel the dog to overcome the 70 resistance of the spring g and release the end of the hoop m which has been held by the dog against the inner side of the flange of the coiling-disk, as shown in Fig. 1.

Instead of the hub being cone-shaped, as shown in the drawings, its end may be curved, or it may be left square, and the end of the arm h of the dog may be curved or beveled, 75 or both the arm h and the end of the hub may be curved or beveled to produce the desired operation of the dog.

To the rear end of the spider N is secured the curved lever n, the other end of which is 80 pivoted to the bell-crank o, which is pivotally secured to the frame, and to this bell-crank is also pivotally secured a rod, p, the other end of which is pivotally secured to the guard-finger P. Another rod, r, is also pivotally secured to said guard-finger, and the opposite 85 end of this latter lever is pivotally secured to the crank s, which is secured to one end of the rock-shaft t, to which is secured the treadle-lever R, to the opposite end of which is secured the weight S. By this system of levers, unless a weight is imposed upon the treadle R the weight S holds the spider N with its hub in a retracted position, as shown in Fig. 1, and the guard-finger P in the position there shown; 90 but if the foot is placed upon the treadle R to overcome and raise the weight S, the spider 95

will be projected, as shown in dotted lines, to force the hoop-coil off the disk, simultaneously throwing down the finger-guard to allow the hoop-coil to be thus thrown off.

5 A plate, T, is pivotally and adjustably secured to the front of the frame at *u*, and by means of a bolt, *v*, a strap, U, is secured to this plate, and the other end of this strap is similarly secured to the weighted lever V, which is fulcrumed at *x* to the top of a projection of the frame A. The opposite end of this lever V is provided with a weight, W, the lower edge of which may be provided with a buffer-spring, *w*, if desired. To a stud-projection, *y*, from the front of this lever, is pivotally secured the guard-bar Y, the lower end of which passes through the guide *z*.

The strap or band U may be made of a single piece of suitable material, or it may be made in segmental sections pivotally secured together at their ends by means of the ears *a'*, which, in coiling, embrace the hoop and guide it.

In practice, with the machine constructed and arranged substantially as above described and the parts in position, shown in Fig. 2, the end of the hoop is inserted under the toe of the dog L. The machine is then started by depressing the lever I, causing the friction-pulley H to come in contact with the driving-wheel C, thus imparting a rotary motion to the coiling-disk and a consequent coiling of the hoop upon the periphery of the disk, and against which it is held by the band U, the weighted lever V securing the proper tension, while the free end of the hoop is kept from flying up by the nipper *b*², which is adjustably secured upon the front face of the plate T. The end of the next hoop presented is inserted under the end of the coiled hoop, and so on until the coil of hoops is as large as desired, the end of the last hoop being kept down upon the coil by the nipper *b*², and can thus be easily nailed. Then pressing upon the lever R the spider will be projected, causing the hub of the spider to release the dog and the ram O to force the coil of hoops off the coiling-disk, the guard P being simultaneously depressed with the advancement of the ram. By releasing the lever R the various parts resume their original positions preparatory to forming another coil, if so desired.

The swinging plate T is adjustable upon its pivot *u* for the purpose of adjusting the distance between the swinging plate T and guard-bar Y to the width of the hoops operated upon.

What I claim as my invention is—

1. In a hoop-coiling machine, and in combination with the coiling-disk, holding-dog, mechanism, substantially as described, for operating said dog, and pulley C, the friction-wheel H, pivoted box F, carrying said wheel, spring

b for raising the pivoted box and friction-wheel from the pulley C, and the connecting-rod J and treadle I for bringing the wheel in contact with the pulley, as and for the purpose specified. 65

2. In a hoop-coiling machine, and in combination with the coiling-disk K and pivoted dog L, having an arm, *h*, the sliding hub *l*, either or both the sliding hub and arm *h*, having a curved or beveled end, substantially as and for the purpose specified. 70

3. In a hoop-coiling machine, and in combination with the coiling-disk K, holding-dog L, arm *h* on said dog, and the hub *l*, either or both the hub *l* and arm *h* having a curved or beveled end, the spider N, sliding on the main shaft and carrying the hub *l*, whereby the hoop is released from the dog and forced off the coiling-disk simultaneously by the treadle and connections, substantially as described, between the treadle and spider, substantially as set forth. 75

4. In a hoop-coiling machine, and in combination with the rotating coiling-disk thereof, the strap U, pivotally secured to the plate T (which is provided with the adjustable nipper *b*²) and to the counterbalanced lever V, and the guard Y, substantially as and for the purposes set forth. 80

5. In a hoop-coiling machine, and in combination with the coiling-disk K, holding-dog L, spider-frame N, hub *l*, curved rod *n*, bell-crank *o*, and rod *p*, the pivoted guard-finger P, and suitable connections between the rod *p* and the treadle, substantially as and for the purpose described. 85

6. In a hoop-coiling machine, and in combination with the coiling-disk K, holding-dog L, sliding spider-frame and hub N *l*, and guard-finger P, the curved rod *n*, bell-crank *o*, rods *p* *r*, arms *s*, and treadle-lever R, substantially as and for the purpose specified. 90

7. In a hoop-coiling machine, and in combination with the coiling-disk, holding-dog, and the strap U, connected at one end to the frame of the machine, the weighted lever V, connected with the loose end of the strap U, and the sliding guard Y, connected with the weighted lever to rise and fall therewith, substantially as and for the purpose specified. 95

8. In a hoop-coiling machine, and in combination with the coiling-disk R, holding-dog L, strap U, lever V, and sliding guard Y, the plate T and pivot *u*, said pivot being adjustably secured to the frame of the machine, substantially as and for the purpose specified. 100

ALEXANDER F. WARD.
